GRINDING MACHINE STEADY REST

Carl G. Flygare and Irving A. Taylor, Worcester,
Mass., assignors to Norton Company, Worcester,
Mass., a corporation of Massachusetts

Application July 20, 1938, Serial No. 220,281

10 Claims. (Cl. 51—238)

The invention relates to grinding machines, and more particularly to a work steadyng rest for a large roll grinding machine.

One object of the invention is to provide a simple thoroughly practical work steadyng rest for a roll grinding machine of the grinding wheel traverse type which is arranged so that the steadyng rest shoes may be readily adjusted from the control station on the reciprocating grinding wheel carriage. Another object of the invention is to provide an improved steadyng rest construction in which both a horizontally adjustable steadyng rest shoe and a vertically adjustable work steadyng shoe are arranged so that they may be readily adjusted from the control station on the reciprocating grinding wheel carriage. Another object of the invention is to provide a steadyng rest having suitable adjustments whereby a wide range of work sizes may be readily steadied without replacing the steadyng rest. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a fragmentary rear elevation of a roll grinding machine of the grinding wheel traverse type having the improved steadyng rest mounted thereon;

Fig. 2 is a cross-sectional view, taken approximately on the line 2—2 of Fig. 1, on a slightly enlarged scale, showing the details of the steadyng rest construction and the adjustment therefor; and

Fig. 3 is a fragmentary sectional view of the lower steadyng rest shoe, showing the application of an adapter and a modified steadyng rest shoe for use in grinding small diameter work pieces.

A roll grinding machine of the grinding wheel traverse type has been illustrated in the drawings comprising a base 10 which supports a swivel table 11. The swivel table 11 supports a rotatable work support including a headstock (not shown) having a headstock center 13 and a footstock (not shown) having a footstock center 14 which are arranged rotatably to support a work piece, such as a roll 12 for a grinding operation. A rotatable grinding wheel 15 is provided for grinding the work piece or roll 12 and is mounted

on a transversely movable slide (not shown) which in turn is supported on a longitudinally reciprocable carriage (not shown) to facilitate a grinding wheel feeding movement and a traversing movement of the wheel relative to the work piece. The details of the grinding wheel mount and its support have not been illustrated since they are not considered to be part of the present invention and are well known features of a roll grinding machine of the grinding wheel 10 traverse type. For details of disclosure not found herein as to the grinding wheel traverse type cylindrical roll grinding machine, reference may be had to the prior United States patent to C. H. Norton No. 1,096,188 dated May 12, 1914, to which 15 reference may be had for details of disclosure not contained herein.

In the operation of a roll grinding machine of the grinding wheel traverse type, it is customary to provide an operator's control station on the reciprocable grinding wheel carriage so that the operator rides back and forth on the wheel carriage as the grinding proceeds. In order to attain one object of the invention, an improved steadyng rest is provided which is arranged so that 25 it may be readily controlled and adjusted from the operating station on the reciprocable wheel carriage during the grinding operation.

As illustrated in the drawings, the improved steadyng rest comprises a steadyng rest frame 20 which 30 is provided on its under surface with a partial dovetailed surface 21 which mates with a correspondingly shaped surface 22 formed on the upper surface of the swivel table 11. A clamping block 23 having a surface mating with a portion 35 of the dovetailed surface on the swivel table 11 is utilized to clamp the steadyng rest frame 20 rigidly upon the swivel table 11. A stud 24 is screw threaded into the frame 20 and passes through a clearance hole in the clamping block 40 23. A nut 25 threaded onto the outer portion of the stud 24 serves to lock the clamping block 23 in position to hold the steadyng rest frame 20 rigid relative to the swivel table 11.

A horizontally adjustable work steadyng shoe 45 30 is arranged to engage the work piece or roll 12 at a point substantially in a horizontal plane with the axis of rotation of the work piece. The shoe 30 is carried by a transversely adjustable slide 31 and is connected thereto by means of 50 a pin 32. The slide 31 is slidably mounted within a transversely adjustable housing 33. The housing 33 is adjustably mounted on the frame 20 and is arranged so that it may be adjusted relative thereto in a horizontal direction either to 55

ward or from the axis of the work piece. The frame 20 is provided with a key or guideway 34 which is fixedly mounted thereto and projects above the surface thereof. A groove 35 formed 5 in the under side of the housing 33 is of sufficient width slidably to engage the side faces of the key 34 to facilitate transverse adjustment of the housing 30. The housing 33 is provided with a T-slot 36 in its under surface by means 10 of which the housing may be clamped rigidly in position on the frame 20 by clamping bolts 37 and 38. This adjustment above described serves to facilitate setting up the steadyrest or for adjusting it when changing from one size work 15 piece to another.

A nut and screw mechanism is provided for adjusting the steadyrest shoe 30 toward and from the work piece before and after a grinding operation and during grinding. A nut 40 is mounted in 20 the left-hand end of the slide 31 and meshes with or engages a rotatable screw 41. The screw 41 is supported in a bearing 42 which is fixedly mounted within the housing 33. The screw 41 is held against endwise movement by means of a 25 flange 43 formed integral therewith which bears against one end of the bearing 42 and a collar 44 which is held in a fixed position on the cylindrical portion 45 of the screw 41 and which bears against the other end of the bushing 42. It will be readily apparent from the foregoing disclosure 30 that when the shaft 45 is turned to rotate the screw 41, a transverse movement will be transmitted by the screw 41 and the nut 40 to move the slide 31 and the shoe 30 either toward or from the work axis.

In order to attain one object of the invention, 35 a suitable mechanism is provided to facilitate adjustment of the steadyrest shoe 30 from the operator's control station on the reciprocating grinding wheel carriage. A manually operable knob 50 is mounted on the right-hand end of a horizontally extending shaft (Fig. 2), the knob and shaft being spaced from and located above the work piece 20 and the knob 50 being located 40 within easy reach of the operator's control station on the reciprocating grinding wheel carriage. The shaft 51 is slidably keyed by means 45 of a key 52 within a rotatable sleeve 53 which is journaled in anti-friction bearings 54 and 55 within a bearing bracket 56. The bracket 56 is 50 rigidly bolted to the upper portion of a vertically extending bracket 57 which is securely fastened to the side face of the steadyrest frame 20.

A sprocket 58 is keyed by means of a key 59 55 with a rotatable sleeve 53 and is connected by a link chain 60 with a sprocket 61. The sprocket 61 is rotatably supported in a bracket 62 which is fixedly mounted on the steadyrest frame 20. The sprocket 61 is provided with a hub portion 63, the 60 periphery of which serves as a bearing surface therefor. The shaft 45 passes through a central aperture in the sleeve 63 and is slidably keyed therein by means of a long key 64. This latter construction is provided to permit a transverse 65 movement of the housing 33 in setting up the rest or in changing from grinding one sized work piece to another.

It will be readily apparent from the foregoing 70 disclosure that in any position of the housing 33, the operator from his control station on the reciprocating carriage may reach over the work piece, grasp the hand wheel 50, and rotate the screw 41 to transversely adjust the position of the steadyrest shoe 30 during the grinding operation.

A lower steadyrest shoe 80 is arranged to engage the under surface of the work at a point below the work axis and between a vertical plane passing through the axis of the wheel and the line of contact between the grinding wheel and the work piece. The shoe 80 is fixedly mounted on an adjustable slide member 81 by means of a pin 82. The slide 82 is supported by a pivotally mounted supporting member 83 which is connected by means of a stud 84 with the frame 20. A rotatable screw 85 is screw threaded into a 10 threaded aperture 86 in the slide 81. The screw 85 is provided with an integral flange 87 which bears against a thrust washer 88 located at the bottom of an aperture 89 which surrounds and 15 guides the slide 81. It will be readily apparent from the foregoing disclosure that rotation of the screw 85 by applying a wrench to the squared portion 90 will cause an adjustment of the slide 81 relative to the supporting member 83 so as to 20 adjust the work steadyrest shoe 80 in a direction substantially toward or from the work axis. This adjustment is provided to facilitate setting up the steadyrest.

In order to adjust the position of the steadyrest shoe 80 during the grinding operation, a 25 mechanism is provided for swinging the supporting member 83 about its pivot 84. This is preferably accomplished by means of a nut and screw mechanism comprising a rotatable screw 91 30 which is rotatably supported in bearings 92 and 93 in the steadyrest frame 20. The screw 91 meshes with or engages a threaded aperture 94 within the sleeve 95 which is slidably supported within an aperture 96 formed in the steadyrest frame. A bracket 97 is fixedly mounted on the right-hand end of the sleeve 95 and is connected by means of a stud 98 with a link 99. The other end of the link 99 is pivotally connected by a stud 100 with a lever or link 101, the lower end of which is pivotally connected by a stud 102 40 with the steadyrest frame 20. The link or lever 101 supports a stud 103 which is pivotally connected to the lower end of a link 104, the upper end of which is connected by a stud 105 with the pivotally mounted shoe supporting member 83. The links or levers 101 and 104 serve as 45 toggle levers to produce a swinging adjustment of the pivotally mounted shoe supporting member 83 to facilitate adjustment of the shoe 80 as the grinding operation proceeds.

The screw 91 is provided with an integral cylindrical shaft 106 which is supported in the bearings 92 and 93 and is held against endwise motion by means of an integral flange 107 formed 55 on the screw 91 and a sprocket 108 which is keyed and fastened to a reduced end portion of the shaft 106. It will be readily apparent from the foregoing disclosure that rotation of the shaft 106 and the screw 91 produces an endwise 60 movement of the sleeve 95 which operates through the links or levers 99, 101 and 104 to swing the shoe supporting member 83 about its pivot 84 to cause the work steadyrest shoe 80 to approach or recede from the work axis.

To facilitate a readily accessible adjustment for the shoe 80, a hand wheel 110 is mounted on the outer end of a horizontally positioned shaft 111, both of which are located above the work piece 12, the wheel 110 being located within easy reach 70 of the operator. The shaft 111 is slidably keyed by means of a key 112 within an aperture 113 in a rotatable sleeve 114 which is journaled in anti-friction bearings 115 and 116. The bearings 115 and 116 are in turn supported within a bear- 75

ing bracket 117 which is rigidly fastened to the vertically extending bracket 57. A sprocket 118 is keyed to the outer end of the sleeve 114 and is connected by means of a link chain 119 with the sprocket 108 which is mounted on the outer end of the feed screw 91. It will be readily apparent from the foregoing disclosure that by rotation of the hand wheel 110, which is readily accessible from the operator's control station on the reciprocating grinding wheel carriage, the screw 91 may be rotated in either direction so as to cause the lower work steadyng shoe 80 to approach or recede from the axis of the work piece.

The shafts 51 and 111 together with the hand wheels 50 and 110 may be moved toward the left (Fig. 2) so that the shafts telescope within the sleeves 53 and 114, respectively, to facilitate loading or unloading the work piece or roll 12 in a vertical direction by means of an overhead crane.

If relatively small work pieces are to be ground with the steadyrest as illustrated in Fig. 2, the housing 33 may be adjusted transversely toward the work axis by loosening the clamping bolts 37 and 38, after which they may be locked in an adjusted position and the remaining adjustment made by rotatably adjusting the feed screw 41.

For relatively small diameter work, such as shown in Fig. 3, an adapter bracket 120 is mounted on the upper surface of the pivotally mounted shoe carrying member 83 and the slide 81 is replaced with a relatively long slide 121 which fits within the aperture 89 and may be adjustably positioned therein by rotation of the feed screw 85.

It will be readily appreciated from the foregoing disclosure that this steadyrest, while adapted for use in grinding large cylindrical objects in a traversing wheel type cylindrical or roll grinding machine, may also be utilized in grinding small diameter work on this type of machine when desired. In either case the work steadyng shoes 30 and 80 may be readily adjusted by the operator without leaving his control station on the reciprocating grinding wheel carriage.

The operation of this improved steadyrest will be readily apparent from the foregoing disclosure. Assuming the steadyrest has been set up for a given sized work piece, the work piece 12 to be ground is placed on centers in the machine and the grinding operation is started, that is, the grinding wheel is rotated and reciprocated longitudinally of the work piece. By manipulation of the hand wheels 50 and 110, the work steadyng shoes 30 and 80, respectively, may be adjusted into supporting and steadyng engagement with the peripheral surface of the work piece 12 and maintained in adjusted position relative thereto during the grinding operation. As the work is ground away, the wheel 50 may be rotated to adjust the steadyrest shoe 30 horizontally, and the steadyrest shoe 80 may be adjusted in a radial direction, substantially vertical, by rotation of the hand wheel 110 which turns the screw 91 to cause the toggle levers 101 and 104 to approach a straight line position as the shoe 80 is fed toward the work axis to maintain it in supporting engagement with the periphery of the work piece during the grinding operation.

It will thus be seen that there has been provided by this invention apparatus in which the various objects hereinabove set forth together with many thoroughly practical advantages are successfully achieved. As many possible embodiments may be made of the above invention and 75 as many changes might be made in the embodi-

ment above set forth, it is to be understood that all matter hereinbefore set forth or shown in the accompanying drawings is to be interpreted as illustrative and not in a limiting sense.

We claim:

1. In a grinding machine steadyrest having a frame, an adjustable work steadyng shoe on said frame, means including a nut and screw to adjust said shoe relative to the frame, and a remote control therefor including a rotatable shaft which is spaced from said screw, a manually operable hand wheel on one end of said shaft, and driving connections between the other end of said shaft and said screw to facilitate adjustment of the shoe.

2. In a grinding machine steadyrest having a frame, a horizontally movable work steadyng shoe on said frame, means including a nut and screw to adjust said shoe relative to the frame, and a remote control therefor including a rotatable shaft which is spaced from and arranged parallel to said screw, a manually operable hand wheel on one end of said shaft, and a chain and sprocket driving connection between the other end of said shaft and screw to facilitate adjustment of said shoe.

3. In a grinding machine steadyrest having a frame, a housing adjustably mounted thereon, means to adjust said housing relative to said frame, a slide within said housing, a work steadyng shoe on said slide, means including a nut and screw to adjust said slide and shoe relative to said housing, and a remote control therefor including a rotatable shaft which is spaced from and arranged parallel to said screw, a hand wheel on one end of said shaft, and a chain and sprocket driving connection between the other end of said shaft and said screw.

4. In a grinding machine steadyrest having a frame, a horizontally adjustable housing on said frame, means to adjust said housing relative to said frame, a slide within said housing, a work steadyng shoe on said slide, means including a nut and screw mechanism to adjust said slide and shoe relative to said housing, a rotatable sleeve which is rotatably supported by said frame and spaced from and parallel to said screw, a chain and sprocket driving connection between said sleeve and said screw, and means including a manually operable hand wheel and shaft to support said wheel which are slidably keyed within said sleeve to facilitate adjustment of said shoe.

5. In a grinding machine steadyrest having a frame, a pivotally mounted shoe supporting member on said frame, a work steadyng shoe adjustably mounted on said member, a pair of toggle levers which are operatively connected to swing said member so as to move the shoe toward or from the work axis, and means including a manually operable nut and screw mechanism to actuate said toggle levers so as to adjust the position of said shoe.

6. In a grinding machine steadyrest having a frame, a pivotally mounted shoe supporting member on said frame, a work steadyng shoe adjustably mounted on said member, a pair of toggle levers which are operatively connected to swing said member so as to move the shoe toward and from the work axis, means including a nut and screw mechanism to actuate said toggle levers, and a remote control therefor including a rotatable shaft which is spaced from said screw, a manually operable hand wheel on one end of said shaft, and driving connections between the other end of said shaft and screw to facilitate adjustment of the shoe.

other end of said shaft and said screw to facilitate adjustment of the shoe.

7. In a grinding machine steadyrest having a frame, a horizontally movable shoe adjustably mounted on said frame to engage and steady a work piece opposite the grinding wheel, a pivotally supported shoe to engage a work piece from below, an independent nut and screw mechanism for independently adjusting each of said 10 shoes, and a remote control therefor including a pair of rotatable shafts spaced from said screws, a manually operable hand wheel on each of said shafts, and driving connections between said shafts and said screws whereby said shoes may be 15 independently adjusted.

8. In a grinding machine steadyrest having a frame, a horizontally adjustable steadyrest shoe arranged to engage the work piece at a point diametrically opposite the line of contact between 20 the wheel and work, means including a manually operable nut and screw mechanism to adjust said shoe, a lower steadyrest shoe arranged to engage the lower surface of the work piece, a pivotally mounted supporting member for said lower shoe, 25 a manually operable nut and screw mechanism to adjust the position of said screw relative to said member, a pair of toggle levers operatively connected between said pivotally mounted shoe supporting member and said frame to facilitate 30 movement of said shoe either toward or from the work axis, and means including a manually operable nut and screw mechanism to actuate said toggle levers.

9. In a grinding machine steadyrest having a frame, a horizontally adjustable steadyrest shoe arranged to engage the work piece at a point diametrically opposite the line of contact between 35 the wheel and work, means including a manually operable nut and screw mechanism to adjust said

shoe, a lower steadyrest shoe arranged to engage the lower surface of the work piece, a pivotally mounted supporting member for said lower shoe, a manually operable nut and screw mechanism to adjust the position of said screw relative to said 5 member, a pair of toggle levers operatively connected between said pivotally mounted shoe supporting member and said frame to facilitate movement of said shoe either toward or from the work axis, means including a manually operable 10 nut and screw mechanism to actuate said toggle levers, a rotatable sleeve which is rotatably supported on said frame and spaced from and arranged parallel to said latter screw, link chain and sprocket driving connections between said 15 sleeve and said screw, and means including a manually operable hand wheel to rotate said sleeve in either direction to facilitate adjustment of said steadyrest shoe.

10. In a grinding machine steadyrest having a 20 frame, an adjustable hollow transversely arranged housing thereon, means to adjust said housing relative to said frame in a transverse direction either toward or from the work axis, a slide within said housing, a work steadyng shoe 25 on said slide, means including a nut and screw mechanism to adjust said slide and shoe relative to said housing, and a remote control therefor including a rotatable sleeve supported by said frame and arranged parallel to said screw, a 30 sprocket on said sleeve, a sprocket on said screw, a link chain driving connection between said sprockets, a shaft slidably keyed within said sleeve, a manually operable hand wheel on said shaft, said shaft being arranged to telescope 35 within said sleeve during a work loading operation.

CARL G. FLYGARE.
